CLAIM

We claim the ornamental designs for a LED lamp, as shown and described.

DESCRIPTION

FIG. 1 is a front view showing an embodiment of our new design for a LED lamp;

FIG. 2 is a right side view of the LED lamp of FIG. 1;

FIG. 3 is a left side view of the LED lamp of FIG. 1;

FIG. 4 is a top view of the LED lamp of FIG. 1;

FIG. 5 is a bottom view of the LED lamp of FIG. 1;

FIG. 6 is a first perspective view of the LED lamp of FIG. 1;

FIG. 7 is a second perspective view of the LED lamp of FIG. 1;

FIG. 8 is a front view showing another embodiment of our new design for a LED lamp;

FIG. 9 is a right side view of the LED lamp of FIG. 8;

FIG. 10 is a left side view of the LED lamp of FIG. 8;

FIG. 11 is a top view of the LED lamp of FIG. 8;

FIG. 12 is a bottom view of the LED lamp of FIG. 8;

FIG. 13 is a first perspective view of the LED lamp of FIG. 8; and,

FIG. 14 is a second perspective view of the LED lamp of FIG. 8.

The portions shown in broken lines are not part of the claimed design but show the environment in which the design is associated.
